UNITED STATES PATENT OFFICE.

LOUIS E. F. WACHTER, OF HARTFORD, CONNECTICUT.

DESIGN FOR A PENDANT FOR WATCHES.

No. 38,576.

Specification for Design.

Patented May 21, 1907.

Application filed March 6, 1907. Serial No. 360,987. Term of patent 14 years.

To all whom it may concern:

Be it known that I, LOUIS E. F. WACHTER, a citizen of the United States, residing in the city of Hartford, in the county of Hartford, in the State of Connecticut, have invented a certain new, original, and ornamental Design for Pendants for Watches, of which the following is a specification, reference being had to the accompanying drawing, forming a part hereof.

The drawing is a view in side elevation of a pendant for watches which embodies the invention.

I claim

The ornamental design for a pendant for watches as shown.

LOUIS E. F. WACHTER.

In the presence of—

HOMER H. SNOW,
W. B. GREELEY.
